UNITED STATES PATENT OFFICE

EDMUND L. MAZURETTE, OF DENVER, COLORADO

RADIATOR

Application filed June 18, 1923. Serial No. 286,435.

My invention relates to radiators of the type used in heating systems, which by conduction, convection and radiation transmit the heat of steam, hot water or other heating fluid, passing through the system, to a room or space in which the radiator is disposed.

It is an object of the present invention to provide in a radiator of the above stated type certain features which combine lightness, compactness and economy in construction with superior efficiency and practicability in use.

Principal among these features is a means whereby the duration of contact of the air with the heated surface of the radiator and the direction in which the air travels along the surface are predetermined and controlled so as to increase the volume of air which can pass over the radiator, minimize waste of heat, prevent damage to walls, draperies and other objects immediately behind the radiator, and provide for the rapid transmission of the heat to the air within the room.

Another distinctive feature of the invention resides in passing the heating medium through the radiator in small volumes and a thin stream, in which form it gives up its heat most readily by rapid cooling and condensing.

The above and other objects all of which will be fully brought out in the course of the following description, I attain by the novel features of construction included in the embodiment of the invention illustrated in the accompanying drawings.

Figure 1 of the drawings represents an end-elevation of two units of a radiator made in accordance with my invention,

Figure 2, a side elevation of the units shown in Figure 1,

Figure 3, a top or plan view of the same,

Figure 4, a fragmentary section taken on the line 4—4, Figure 2, and

Figure 5, a fragmentary elevation of three units assembled into a radiator.

Like reference numerals designate corresponding parts throughout the views.

Referring further to the drawings, each unit of the radiator consists of a single flue 1 of oblong horizontal section, arched at its

top and bottom and provided with suitably formed legs 1a when desired for its support on the floor of a compartment in which the radiator is installed.

The side-walls of the unit have adjacent 55 the top and bottom of the flue, outwardly projecting hollow bosses which provide ports 3 for the ingress and egress of the heating fluid, and egress of condensation, and where the radiator is composed of a plurality of 60 units as illustrated in the drawings, connecting bosses 2 at the opposed sides of the units are placed in register with each other for the passage of the heating fluid and condensation from one unit to another in a circulatory 65 movement.

The units are furthermore provided with air-relief ports 4.

The flue provided by each unit is interiorly 70 of short length in comparison with its width and height so that the heating medium passing through the flue is spread in the form of a thin stream or sheet to secure rapid transmission of its heat to the walls of the unit.

The inner surfaces 6 of the walls of each 75 unit are plain and smooth to offer the least resistance to the flow of the heating medium and condensate and to simplify construction.

The outer surfaces of both side-walls of the inner units A of a radiator and the outer 80 surface of one of the side walls of the outer units B of the same, are provided with a plurality of parallel ribs 7 inclined at an angle upward from the back and bottom of the units and spaced apart to form a series 85 of correspondingly extending channels 8 of considerable depth, and the end-walls of the units may have vertical ribs 9 which likewise provide channels 10 into which the air inside 90 the room may enter.

In the use of the radiator composed of units of the above described form and construction, the heating fluid passing through the flue in the form of a thin stream or sheet rapidly transmits its heat through the walls 95 of the unit by conduction whence the heat is transmitted to the air within the room and to adjacent objects by convection and radiation.

Owing to the smooth surfaces at the inside 100 of the flue, the heating medium flows in an

unobstructed stream and without other than frictional resistance between the ingress ports and egress ports, and thereby transmits its heat to the walls of the unit at its maximum temperature in a substantially continuous operation.

- Owing to the presence of the ribs and channels, the outer surfaces of the units are of considerably greater superficial extent or area than the inner surfaces of the same and thereby effect a closer equalization of the rates of heat transmission by conduction and convection and a large increase in effective heating surface and corresponding rating.
- It is to be observed that this increased heating surface is obtained without increase in the bulk, weight or cost of production of the radiator and that in fact, in proportion to the rating, these three essential factors are considerably decreased.

The channels slanting upwardly from the back and bottom of the units as hereinbefore described, have, however, other functions that are of vital importance in the operation of the radiator insomuch as they greatly enhance the efficiency and practicability of the same.

The value of the channels will be readily apparent from the fact that they increase the volume of air contacting with the heating surfaces of the radiator, that they provide for the continuous movement of this volume of air, and that by controlling the direction of travel of the air, they provide a greatly enlarged air orifice which makes possible a correspondingly increased volume of air that can travel over the heating-surfaces, with greater average temperature differences between the air and the heating medium, the air volume being in fixed ratio with the heating surface regardless of the height of the radiator, and eliminating dead heating surface.

The direction of the channels moreover, causes the air currents to flow away from the wall behind the radiator, thus protecting the wall, draperies or other adjacent objects from the damaging effects of a vertically ascending or uncontrolled column of highly heated air produced in the operation of radiators of types heretofore used, thus acting as a shield and preventing rapid and wasteful flow of heat through the wall due to increased temperature difference between its inside and outside surfaces.

The simple flue construction of the units, combines simplicity with increased efficiency owing to the small volume of the heating medium passing through the flue, in proportion to the area of wall surface which it serves, and the channeled construction of the units, as shown and described, is highly advantageous for the reasons hereinbefore set forth.

The positive control of the direction of

the air travel over the heated surfaces and the absence of obstructions to said travel, limit the duration of air-contact with the heating surfaces and thereby render every part of the surfaces active at all times. It moreover, regulates the air circulation about the room or enclosure in which the radiator is installed, by the production of a multiplicity of currents which aid in rapidly heating the room to the desired temperature.

The buttressed arch shape of the outer surface of the walls of the units adds greatly to their strength and lends itself readily to the spiral form of ascending columns of air, and the channels inclined at an angle are also valuable from an economic point of view by preventing damage to the walls, draperies and other adjacent objects and by preventing waste of heat through the walls as stated hereinbefore.

In constructing a radiator of units made in accordance with my invention as hereinbefore described, it is desirable that the outer surfaces of the outer units be smooth and without channels, as illustrated in Figure 5, to permit of ornamentation of the exposed surfaces, and to eliminate unsightly ribs where they are of least advantage.

It will be apparent that the slanting channels are most effective between the units, more particularly since in ordinary radiator construction the intermediate units are not as fully exposed to the atmosphere as are the outer units and do not permit of the passage of sufficient air along their heating-surfaces to give full thermal value of the radiated heat.

The ribs may be extended so that those of the adjoining units can meet to conjointly form slanting channels for the circulation of the air as has been shown at 12 in Figure 5 and in this modified construction it is advantageous that part of the ribs be of smaller height as shown at 13, to give sufficient space for the purpose of cleaning the channels of the radiator between the units thereof, whenever necessary.

What I claim and desire to secure by Letters Patent is:

1. A multi-section radiator comprising assembled units, opposed side walls of which have a multiplicity of parallel ribs slanting from adjacent the bottom and rear edges of the walls, to adjacent the top and front edges of the same, some of the ribs of the units adjoining one another to cooperatively form channels for the slantingly upward passage of air between the units, and ribs between the adjoining ribs being of lesser width to provide within the channels, separated grooves assisting in the passage and heating of air, and permitting the insertion of a brush to clean a multiplicity of ribs at one operation.
2. A multi-section radiator comprising as

sembled heating-units each composed of a hollow vessel the side walls of which are adapted for the transference of heat to outside air, said walls having exterior parallel 5 ribs forming grooves slanting in straight lines from points along the bottom edges and rear upright edges of the walls to points along the top edges and front upright edges of the same, and the units being assembled 10 side by side with the grooves in opposed sides registering with each other to jointly provide a series of straightway channels between the units for the slantingly upward passage of air in the direction determined by the relation 15 of the points between which the grooves extend, and with the ribs spaced from each other for the insertion of a brush to clean a multiplicity of ribs at one operation.

In testimony whereof I have affixed my
20 signature.
